DESIGN FOR A TOILET SEAT

Peter J. Sperzel, Minneapolis, Minn., assignor to
Morden J. McCabe, Minneapolis, Minn.

Application December 20, 1943, Serial No. 112,061

Term of patent 14 years

(Cl. D4—5)

To all whom it may concern:

Be it known that I, Peter J. Sperzel, a citizen of the United States, residing at Minneapolis, in the county of Hennepin and State of Minnesota, have invented a new, original, and ornamental Design for a Toilet Seat, of which the following is a specification, reference being had to the accompanying drawing, forming part thereof.

Referring to the drawing:

Fig. 1 is a top plan view of the novel and decorative toilet seat;

Fig. 2 is a side elevation thereof;

Fig. 3 is a bottom plan view of one of the seat pads as it would appear in a normally raised position; and

Fig. 4 is a transverse sectional view taken on line 4—4 of Fig. 1 to illustrate the contour of the marginal and central portions of the seat pad.

I claim:

The ornamental design for a toilet seat, as shown and described.

PETER J. SPERZEL.
